UNITED STATES PATENT OFFICE.

HERBERT CORRAL, OF HELENSBURGH, AND BERTRAM AMBROSE STEVENS, OF CLYDEBANK, SCOTLAND, ASSIGNEES TO THE SINGER MANUFACTURING COMPANY, OF ELIZABETH, NEW JERSEY, A CORPORATION OF NEW JERSEY.

SEWING MACHINE.

Application filed October 11, 1920. Serial No. 416,147.

To all whom it may concern:

Be it known that we, HERBERT CORRAL and BERTRAM AMBROSE STEVENS, both subjects of the King of the United Kingdom of Great Britain and Ireland, and residing at Helensburgh, Dumbartonshire, Scotland, and Clydebank, Dumbartonshire, Scotland, respectively, have invented a certain new and useful Improvement in Sewing Machines, of which the following is a specification.

This invention relates primarily to improvements in listing or bagging machines designed for stitching together along the selvedge edge, lengthwise, of long lengths of piece goods by means of a loose chain-stitch seam previous to milling, scouring or dyeing whereby to prevent the edges or lists from curling in during the milling, scouring or dyeing operation.

The invention provides inter alia, an improved stitch-forming mechanism operating in conjunction with a continuous rotary feed mechanism, it being understood that such mechanisms are applicable to chain-stitch sewing machines of other types.

In the accompanying drawings Fig. 1 is a side elevation and Fig. 2 a front end elevation of a sewing machine embodying the invention. Figs. 3 and 4 are detail elevations at right angles to each other showing a pendulous carrier forming a common support for the needle-bar and looper carrier; Fig. 5 is a detail view of an alternative form of cam for imparting oscillatory movements to the pendulous carrier. Figs. 6 and 7 are detail elevations at right angles to each other of the looper actuating mechanism. Figs. 8 and 9 are detail views of the connections for actuating the power transmitter and presser. Fig. 10 is a detail view showing the connection between the feed-wheel and a drum serving to carry the pieces being stitched.

Referring to the drawings, 1 denotes the main shaft to which is adapted to be clutched the pulley 2, and which is provided with a crank 3 connected by a pitman 4 to a crank 5 on the needle-actuating rock-shaft 6. To a crank 7 on the rock-shaft 6 is pivotally connected one end of a link 8 the other end of which is pivotally connected to a collar 9 fixed to the needle-bar 10 carrying the needle 11 and mounted

for reciprocation in bearings 12, 13 in a movable support in the form of a pendulous carrier 14 pivoted at its upper end at 15 to the head of the machine frame and guided at its lower end by stationary guides 16; the axis of the pivot 15 being parallel to the main shaft 1.

Co-operating with the needle 11 in the production of stitches is the chain-stitch looper 17 fitted to a carrier 18 mounted to rock on a pin 19 projecting laterally from an arm 20 of a sleeve 21 loosely surrounding a pin 22 projecting from, and secured by screws 23 to, the lower end of the pendulous carrier 14.

The carrier 14 thus presents a common movable support for the needle-bar and looper-carrier.

Loop-seizing movements are imparted to the looper 17 through the intermediary of a link 24 of which one end is pivotally connected to a pin 25 fixed to the looper-carrier 18, the other end of the link 24 being pivotally connected to one arm 26 of a bellcrank lever which is pivoted at 27 and of which the other arm 28 is connected to the lower end of a pitman 29, the upper end of which is connected to a crank pin 30 on a crank 31 on the needle-actuating rock-shaft 6.

It will be seen that the rocking movement of the shaft 6 produces rocking movement of the looper-carrier 18 on the pin 19.

Needle-avoiding movements are imparted to the looper 17 by mechanism including an eccentric 32 on the main shaft 1 which imparts rocking movement to a yoke 33 clamped by a screw 34 to the sleeve 21, resulting in rocking movement of the looper carrier 18 around the axis of the pin 22.

Swinging movements of the pendulous carrier 14 on the pivot 15 are effected by mechanism including a cam 35 removably secured to the main shaft 1 and engaged by a follower 36 carried by an arm 37 fixed to the lower end of the pendulous carrier 14.

It will be seen that oscillatory movements of the pendulous carrier 14 produce positively effected simultaneous lateral movements of the needle and of the looper in the direction of feed.

The feeding mechanism includes a spiked feed wheel 38 positively rotated continuously in one direction, being driven from the main shaft 1 through the intermediary of

bevel gears 39, 40, worm 41 and worm-wheel 42.

It will be understood that when it is desired to change the length of stitch the cam 35 is replaced by a cam of different contour such as 35¹, and certain of the gears for driving the feed-wheel 38 are replaced by other gears.

Co-operating with the feed-wheel 38 is 10 a cloth-presser 44 carried by one arm 45 of a lever pivoted on a pin 46 and having a rearwardly extending arm 47 to which is pivotally connected the upper end of a link 48 having at its lower end a slot entered by 15 a pin 49 on an arm 50 on a shaft 51 to which is fitted a manually operable lever 52, the pin and slot forming a lost motion connection. Fixed to the shaft 51 is a cam 53 engageable with a blade spring 54 fitted to 20 one arm 55 of a lever fulcrumed at 56 and having arms 57 and 58.

When the lever 52 is raised, the cam 53 rocks the lever 55, 57, 58 in opposition to the spring 59 and the stud 60 carried by the 25 lever arm 57 presses against the thrust stud 61 fitted in the boss of the driving pulley 2 whereby to effect endwise movement of the pulley 2 on the shaft 1 into frictional driving relation with the fly-wheel 62 fixed 30 to the shaft 1.

The lever arm 58 carries a brake 63 engageable with a brake surface on the fly-wheel 62.

Surrounding the pin 46 is a coil spring 64 35 of which one end enters an aperture in the pin 46 and the other end engages the lever arm 45.

When the lever 52 is raised the pin 49 40 rises in the slot 50; the spring 64 then effects depression of the presser.

Depression of the lever 52 causes the presser to be raised in opposition to the spring 64, the pulley 2 is disengaged from the fly-wheel 62 and the brake 63 applied.

The pin-and-slot connection 49, 50 permits rise and fall of the presser for different thicknesses of material without affecting the clutch.

As shown in Fig. 10, the feed wheel 38 50 has a driving crank connection 65 with a spider 66 carrying a drum or cylinder 67 coaxial with said feed-wheel and of sufficient length to accommodate the width of the pieces being stitched.

What we claim is:—

1. In a sewing machine, in combination, a needle-bar, a looper-carrier, a looper, a movable support for said needle-bar and looper-carrier, a drive shaft mounted in-

dependently of said support, an actuating connection between said shaft and said needle-bar, and another actuating connection between said shaft and said looper-carrier, a feeding member, positively acting means for imparting movements to said feeding member, and means for vibrating said support in the direction of feed. 60 65

2. In a sewing machine, in combination with the machine frame, a pendulous carrier pivoted to said frame, a needle-bar mounted for reciprocation in said carrier, a looper sustained by said carrier, a feeding member rotatable around an axis parallel to the pivot of said carrier, means for imparting rotary movement to said feeding member, and means for oscillating said carrier about its pivot. 70 75

3. In a sewing machine, a main shaft, a pendulous carrier pivoted on an axis parallel to said shaft, a needle-bar mounted for reciprocation in said carrier, a looper sustained by said carrier, a feeding member rotatable around an axis parallel to said shaft, positively acting connections between said shaft and said feeding member for imparting continuous rotary movement to said feeding member, and a cam on said shaft for oscillating said carrier about its pivot. 80 85

4. In a sewing machine, in combination with the machine frame, a main shaft, a pendulous carrier pivoted to said frame, a needle-bar mounted for reciprocation in said carrier, a looper sustained by said carrier, connections between said shaft and said needle-bar for imparting reciprocatory movements to said needle-bar, connections between said shaft and said looper for imparting stitch-forming movements to said looper, and a cam on said shaft for oscillating said carrier on its pivot to effect lateral vibrations of said needle-bar and looper. 90 95 100

5. In a listing machine, in combination, stitch forming mechanism including a reciprocatory needle and a looper, means for imparting stitch-forming movements to said needle and looper, means for effecting positively lateral movements of said needle and looper, a rotatable feeding member, means for effecting continuous rotary movement of said feeding member, a work-carrying drum coaxial with said feeding member, and a driving crank connection between the feeding member and the said drum. 105 110 115

In testimony whereof we have signed our names to this specification.

HERBERT CORRAL.

BERTRAM AMBROSE STEVENS.
